AUTOMATIC REFUSING MECHANISM

William H. Frank, Joseph A. Messing, and Harrison J. L. Frank, Detroit, Mich., assignors to Bulldog Electric Products Company, Detroit, Mich., a corporation of West Virginia

Original application April 19, 1933, Serial No. 666,786, now Patent No. 2,000,016, dated May 7, 1935. Divided and this application February 2, 1935, Serial No. 4,606

6 Claims. (Cl. 200—126)

This application relates to circuit protective devices, and is a division of a prior application, Serial No. 666,786, filed April 19, 1933, now Patent Number 2,000,016, of May 7, 1935.

5 It is proposed by the present invention to combine with a multiple fuse wheel or body of the type disclosed in the aforesaid application a mechanism which automatically rotates the wheel upon the blowing of a fuse, so as to introduce a second fuse into the circuit, the device in this regard operating as an automatic refusing circuit protective device. The mechanism of the instant application is so constructed that a limited number of refusing operations occur automatically, two being the number chosen in the embodiment illustrated. The operation is such that when a fuse blows and opens the circuit, a second fuse will automatically be placed into the line to close the circuit once more; and when this second fuse blows, a third fuse will automatically be placed into the line; however, when the third fuse blows, the circuit will remain open and the device will no longer function automatically, but must be reset by the operator, who must perform this operation manually. Limiting the number of automatic re-fuse operations that can take place before the operator is called upon to close the circuit and reset the device is desirable since it prevents all of the fuses being successively put 10 into a circuit that happens to be continuously overloaded or contains a continuous short circuit.

In the embodiment of the invention illustrated there is provided a spring which is the motivating 35 force in the matter of automatic re-fusing and the spring is so constructed that it is re-wound, after it has lost its original tension, each time the operator resets the device, i. e., after the third of the three fuses in a group has been blown.

40 A further object is the provision of a mechanism of the character described above which is so constructed that one handle serves as a spring-winding handle, and a handle for resetting the device, and further is equipped with a contact arm so that it may serve as a switch handle for permitting manual switching operations.

A further object is the provision of a mechanism of the character described above, in combination with a multiple fuse wheel or body, which 50 is so constructed that the mechanism, and the wheel or body, may be removed from the casing of the device as a unit and replaced by another unit of the same character, when replacement is considered necessary.

55 A further object is the provision of a circuit

protective device including a thermal or warping element, the device being constructed to rupture the circuit automatically on overload, and to be moved to close the circuit automatically shortly thereafter, the means for moving the operating parts of the device being independent of the thermal element. In this respect, the instant application resembles the copending applications, Serial Nos. 667,149—667,152, inclusive, filed April 21, 1933, on automatically resetting circuit 10 breakers.

Still further objects of the present invention will presently appear upon reference to the following detailed description of an embodiment of the same disclosed in detail in the accompanying 15 drawings. In these drawings,

Fig. 1 is a top plan view, with the cover removed, of an automatically re-fusing circuit protective device, employing a wheel such as has been previously disclosed in application Serial No. 20 666,786, now Patent No. 2,000,016, of May 7, 1935, as the multiple fuse element;

Figs. 2 and 3 are, respectively, elevational section and end section views of the same, as if on lines 2—2, 3—3 of Fig. 1, parts being cut away 25 for purpose of clarity;

Fig. 4 is a view of a modified form of indexing arrangement capable of being used in the device of Figs. 1-3;

Fig. 5 is a view similar to that of Fig. 2 but 30 with the parts shown in a second position;

Fig. 6 is a partially cutaway elevational section of the device as if from the opposite side of the device from the view of Figs. 1-3, with the thermal element shown as warped due to an overload 35 and just prior to its cooling or returning position.

The circuit protective device of this case employs as the operated element a wheel which may be of the construction shown in application Serial No. 666,786, now Patent No. 2,000,016, of 40 May 7, 1935. The device includes a cup-shaped base 140 adapted to be closed by a cover 141 through whose slot 142 projects a manual switching arm 143, provided for purposes to be described later. The opposite wall of the base 140 and of 45 the cover 141 are provided with semi-circular bosses 144—145 having registering semi-circular grooves which provide bearings for the ends of the operating shaft 146 of the device. It is observed that the cover 141 is completely detachable 50 from the base and the contained parts merely by sliding it upwardly and over the end of the handle 143.

The operating shaft 146 supports the wheel "W" which is provided with a number of fuses 55

"F", (twelve indicated), any one of which may be brought in station with and so as to connect the upstanding contacts 147-148, one of which, 147, is connected by a lead 149 to the live side 5 of the line through a second pair of contacts 150 adapted to be engaged by the bridging end of the switch arm 151, and the other of which is connected to the load side of the line by a lead 152 and through a thermal bimetallic warping element 10 153. The interior of the wheel communicates with the interior of the shaft, which is hollow, in accordance with the principles disclosed in Fig. 1 of the aforesaid application, so that gases from the explosion chambers in the wheel may vent 15 through the shaft to the atmosphere.

The arm 151 is rigidly connected to the manual switching arm 143 which in turn is provided with a pin 154 disposed in a slot 155 in a boss 156 projecting upward from the base, the pin 20 154 journaling the handle 143 so that the latter, when moved, can cause its arm 151 to close the circuit through the contacts 150.

The fuse wheel "W" is rotatable on the shaft 146 and is connected to a ratchet wheel 160, in 25 any suitable manner, as for example by a pin 161 projecting from the fuse wheel into the ratchet wheel whereby the two wheels rotate in unison on the shaft. For cooperation with such ratchet wheel there is provided a pawl 162 pivoted 30 at 163 to a crank 164 keyed to the operating shaft 146, the pawl being biased towards the teeth of the ratchet by means of the pawl spring 165. The crank 164 has a lug 165a in line with handle 143 and adapted to engage the latter, as will be later 35 mentioned. Fixed to the end of the operating shaft which projects through a slot 166 of the handle 143 is one end of a clock spring 167 whose other end is hooked around a lug 168 of the base 140, and it will be observed that this spring 40 constantly tends to rotate the shaft counterclockwise, Fig. 2.

Also rotatably mounted on the shaft, adjacent to that side of the wheel "W" opposite ratchet wheel 160 is an indexing plate 170 having a number of pins 171 corresponding to the number of fuses on the wheel "W", and this plate is connected to wheel "W" in any suitable manner, as for example by a pin 172 projecting from the fuse wheel into the index wheel, so as to rotate 45 thereof. Cooperating with this indexing plate is the bimetallic arm 153 connected in the load circuit so as to be responsive to conditions of the load, the bimetallic arm warping on overload and returning thereafter in cooling. The arm 153 is 50 guided by and connected to axle 146 by a link 180 whose slot 181 receives the axle, and this link, pivoted at 182 to the arm 153, contains a pair of stops 173-174.

The operation of the device is as follows: 55 Assume the parts to be in the position of Fig. 2, with the circuit closed from line contact 150, through switch arm 151, and the other line contact 150, then through flexible lead 149 to contact 147, then through the fuse "F" in station 60 to the contact 148, then through flexible lead 152 to one of the binding posts at the base of the warping arm 153, then through the warping arm to the other binding post and to the load.

When an overload occurs the fuse "F" which 65 happens to be in station with contacts 147-148 will of course blow. This ruptures the circuit, after the fuse has attained sufficient temperature to blow. During the heating of the fuse the warping element 153 also becomes heated by the over- 70 load condition and is so calibrated that it warps 75

to such a position (Fig. 6) that its stop 174 becomes disengaged from the pin 171 resting thereon. The spring 167 therefore rotates the shaft and the indexing plate 170 counterclockwise (Fig. 2), clockwise, Figs. 4 and 6. Rotation 5 of the shaft causes rotation of the crank 164 counterclockwise and pawl 163 picks up ratchet 160 to move it one station. Such rotation of the ratchet wheel is accompanied by rotation of the fuse wheel "W" and accordingly another fuse is 10 presented in station with contacts 147-148, to close the circuit once more.

Pin 171 of the indexing plate, which had been in engagement with the stop 174, now engages stop 173 which moves into the path of the pins 15 171 during the time that arm 153 warps on overload. Engagement of pin 171 by stop 173 therefore prevents the further movement of the parts at this time. This engagement stops all movement of the parts and indexes the parts so that 20 alignment of a fuse properly with respect to contacts 147-148 is assured.

When the thermal element 153 cools, after its momentary warping, stop 173 moves out of the path of pin 171 and the indexing wheel is free 25 to rotate in concord with rotation of the crank 164, but only until the next adjacent pin 171 engages stop 174, which returns into the path of pins 171 on cooling of the element 153.

If the overload is still on the line, or if after 30 an interval of proper load condition of the line, an overload again occurs on the line, the above mentioned cycle of operations will take place once again. However, when the second cycle of operations terminates it will be found that stop 35 165a of crank 164 is in engagement with the handle 143. This prevents further movement of the parts until the handle 143 is manipulated. That is to say, this places the parts in closed circuit 40 position after two fuses have been blown, ready for another fuse blowing on overload, but locks the parts so that upon this last mentioned, or third fuse blowing, there will be no automatic 45 re-fusing until the handle 143 is manipulated. Therefore the device will be found to provide three overload circuit ruptures with the last one leaving the circuit open until the operator manipulates the handle 143.

When he does this, he first opens the already 50 open circuit by causing the switch arm 151 to leave contacts 150. Movement of the handle 143 to the right from the position of Fig. 2 moves the crank 164 back to the original position (Fig. 2) and rewinds the spring 167. This is a resetting 55 operation which places the parts in position to go through three circuit ruptures and two automatic re-fusings with the last circuit rupture not accompanied by automatic re-fusing. The resetting operation is not accompanied by movement of ratchet 160, wheel "W", or plate 170.

The mechanism above described can very well 60 be called a limited cycle automatic re-fusing circuit protective device, the limited cycle description being appropriate because of the fact that the cycle of automatic re-fusing is not continuous 65 but terminates after three circuit ruptures and two automatic re-fusings. In this respect the instant application resembles the copending application Serial No. 667,152, filed April 21, 1933, relating to a limited cycle automatically resetting 70 circuit breaker.

In Fig. 4 there is shown a modification wherein 75 the indexing stops 173-174 are formed directly on the arm 153.

It will be observed that the entire mechanism 75

on the shaft 146 can be removed as a unit from the base and replaced, so that after all of the fuses on the wheel "W" have been blown, an electrician can be called in by the inexperienced 5 householder to replace the used wheel "W" by a fresh wheel. This the electrician does by sliding the indexing plate off, sliding the used wheel off the shaft 146, replacing the same by a fresh wheel, and returning the old indexing plate.

10 Now having described the device illustrated in the drawings, reference will be had to the following claims for a determination of the scope of the invention.

We claim:

15 1. In a multiple fuse device, a body having fuses thereon, means for moving the body for refusing the circuit, as fuses blow, means for limiting the number of refusing operations of the first mentioned means, and reset means manually operable to render the limiting means inoperable and restore the operability of the refusing means.

20 2. In a multiple fuse circuit protective device, automatically operating means cyclically tending to rupture the protected circuit on the blowing of a fuse and then to establish the circuit through another fuse, a circuit responsive element controlling movement of said means in cycles and operating to hold said means in circuit established position or to release said means so that 25 the same may rupture the protected circuit.

25 3. In a multiple fuse circuit protective device, automatically operating means cyclically tending to rupture the protected circuit on the blowing of a fuse and then to establish the circuit through another fuse, a circuit responsive element controlling movement of said means in cycles and operating to hold said means in circuit established position or to release said means 30

so that the same may rupture the protected circuit, the means, though controlled by the element, operating without the aid of the element.

4. In a circuit protective device, circuit closing means, a spring motor so connected to said circuit closing means as to cause the latter to open and close the circuit cyclically and automatically, means for limiting the number of cycles of operation of the motor and for inhibiting the motor against further operation when the parts of the device have come to rest in circuit open position after the limited number of cycles of operation have taken place, and manually operable means operable to close the circuit and rewind the spring of the motor. 5

10 5. In a circuit protective device, circuit closing means, a spring motor so connected to said circuit closing means as to cause the latter to open and close the circuit cyclically and automatically, means for limiting the number of cycles of operation of the motor and for inhibiting the motor against further operation when the parts of the device have come to rest in circuit open position after the limited number of cycles of operation have taken place, and manually operable means 20 25 operable to close the circuit and rewind the spring of the motor and also operable for manual switching.

6. In a multiple fuse protective device, a multiple fuse element, a motor driven automatically 20 operating fuse renewing mechanism therefor, including a motor detachably connected to the element, the element being readily separable from the mechanism as a whole so as to be replaceable without disturbing the motor of the mechanism. 25
